US00D994689S

(12) **United States Design Patent** (10) **Patent No.:** **US D994,689 S**
Dascola et al. (45) **Date of Patent:** **** Aug. 8, 2023**

(54) **DISPLAY SCREEN OR PORTION THEREOF WITH GRAPHICAL USER INTERFACE**

(71) Applicant: **Apple Inc.**, Cupertino, CA (US)

(72) Inventors: **Jonathan Dascola**, San Francisco, CA (US); **Allison W. Dryer**, San Francisco, CA (US); **Robert Garcia**, San Francisco, CA (US); **Bradley William Griffin**, Redwood City, CA (US); **Aurelio Guzmán**, San Jose, CA (US); **Stephen O. Lemay**, Palo Alto, CA (US); **Richard D. Lyons**, San Francisco, CA (US); **Grant R. Paul**, San Francisco, CA (US); **Philipp Rockel**, San Francisco, CA (US); **Christopher Wilson**, San Francisco, CA (US); **Giancarlo Yerkes**, Menlo Park, CA (US)

(73) Assignee: **Apple Inc.**, Cupertino, CA (US)

(**) Term: **15 Years**

(21) Appl. No.: **29/850,603**

(22) Filed: **Aug. 22, 2022**

Related U.S. Application Data

(63) Continuation of application No. 29/776,213, filed on Mar. 29, 2021, now Pat. No. Des. 967,839, which is a continuation of application No. 29/732,877, filed on Apr. 28, 2020, now Pat. No. Des. 914,714, which is a continuation of application No. 29/649,959, filed on Jun. 4, 2018, now Pat. No. Des. 886,124.

(57) **CLAIM**

The ornamental design for a display screen or portion thereof with graphical user interface, as shown and described.

DESCRIPTION

FIG. 1 shows a display screen or portion thereof with graphical user interface showing our new design; FIG. 2 shows a second image thereof; and, FIG. 3 shows a third image thereof.

The peripheral dashed broken lines illustrate a display screen or portion thereof, and form no part of the claimed design.

The relatively dark dashed lines surrounding the circle forms part of the claimed design.

FIG. 3

FIG. 2

FIG. 1

UNITED STATES PATENT AND TRADEMARK OFFICE
CERTIFICATE OF CORRECTION

PATENT NO. : D994,689 S
APPLICATION NO. : 29/850603
DATED : August 8, 2023
INVENTOR(S) : Jonathan Dascola et al.

Page 1 of 1

It is certified that error appears in the above-identified patent and that said Letters Patent is hereby corrected as shown below:

On the Title Page

DESCRIPTION

Column 2

Insert the following statements after Line 9 (at the end of the DESCRIPTION section):

--The appearance of the graphical user interface transitions between the images shown in FIGS. 1-3.
The process or period in which one image transitions to another forms no part of the claimed design.--
